WALTER P. MURPHY, OF CHICAGO, ILLINOIS.

SHEET-METAL END STRUCTURE FOR RAILWAY-CARS.

1,263,458.

Specification of Letters Patent. Patented Apr. 23, 1913.

Application filed November 4, 1912. Serial No. 729,239.

To all whom it may concern:

Be it known that I, WALTER P. MURPHY, a citizen of the United States, residing at Chicago, in the county of Cook and State of Illinois, have invented certain new and useful Improvements in Sheet-Metal End Structures for Railway-Cars, of which the following is a specification.

My invention relates to the construction 10 of railway cars and particularly railway box or house cars; and the invention has for its object to provide an improved metal end structure for railway cars which may be used to take the place of the usual wooden 15 end either in a new car or to replace a worn out or damaged end of an old car.

The invention consists in constructing the 20 end of one or more sheets of metal, preferably more than one, which are relatively thin, for the sake of lightness and so as to give a maximum inside length for the corresponding outside dimension, and are formed with ribs or corrugations disposed so that the end structure will be able to withstand 25 the various stresses to which it is subjected when the car is in service. The end itself is directly subjected, for example, to shocks and stresses from the cargo of two different sorts, both due to the inertia of the cargo 30 when the train starts or stops or makes any relatively quick change in speed. That is, the end is subjected to local thrusts of articles such as pipes, rails, and the like, which are heavy, relatively small in cross section, 35 and because of their shape, liable to displacement with respect to the bulk of the cargo. These local thrusts are such as to dent or bend a thin metal end unless the same is properly reinforced. The cargo, in 40 the second place, is apt to slip or be displaced as a whole and so thrust against the car end when the train starts or stops. The end must be so constructed and so secured to the framing of the car as to withstand 45 shocks of this sort. In addition to the stresses exerted by the shifting of the cargo the end of a railway car is subjected, along with the rest of the superstructure, to certain diagonal stresses resulting from the 50 tendency of the car to weave or distort on diagonal lines and to the tendency of the superstructure to swing or rock from side to side on the end frame. The ordinary wooden car end is not well calculated, even 55 when new, to withstand stresses of this sort. Moreover, it is usually the first part of the

car which is damaged or weakened, because of the cargo thrusts above noted, and when thus damaged and weakened its capacity for resisting the tendency of the car to 60 weave or swing from side to side or otherwise become distorted and racked is still further decreased.

The present invention provides a metal 65 car end which, although made of relatively thin sheets of metal, is very strong and rigid as against all of the stresses to which a car is necessarily subjected when in service. That is, the sheet or sheets constituting the end are formed with ribs so disposed 70 and the structure is so secured to the framing of the car that it not only serves to withstand the shocks and pressures exerted against it by the cargo but also serves to strengthen and rigidify the superstructure 75 of the car as against weaving and other like strains.

The invention is illustrated, in a preferred embodiment, in the accompanying drawing wherein—

Figure 1 is an end elevation of a railway 80 car constructed in accordance with my invention;

Fig. 2, a sectional view taken on line 2—2 of Fig. 1, and

Fig. 3, a sectional plan on line 3—3 of Fig. 1.

Like characters of reference designate 90 like parts in the several figures of the drawing.

Referring to the drawing, 10 designates one of the end sills of a railway car, 11 the corresponding end plate, and 12 the side girders or belt rails. The end structure consists, in this embodiment of the invention, of an 95 upper end sheet 13 and a lower end sheet 14. The upper edge of the upper sheet is secured to the end plate by bolts 15 which also extend through the end fascia 16. The lower edge of the lower sheet 14 is formed 100 with the inturned flange 17 secured by bolts 18 to the end sill 10, the flange 17 preferably extending under the flooring 19 of the car. The sheet 13 overlaps the sheet 14 and the two are secured together by the rivets 20. 105 Both end sheets are formed with flanges 21 on their vertical edges which are secured by means of the bolts 22 to the corner posts 23. As the corner posts of a railway car ordinarily are not strongly enough secured 110 to the rest of the framing of the car to withstand horizontal stresses, the posts be-

ing primarily intended to be load carrying members, I preferably provide means for securing the side flanges 21 of the end sheets to the side girths 12 of the car. To this 5 end gusset plates 24 are provided which, as shown, are secured to the side girths by means of the bolts 25 and attached to the flanges of the upper and lower plates by means of the rivets 26. As this connection 10 is made at the place where the upper and lower sheets overlap it serves also to strengthen the riveted joint between the sheets.

One or both of the sheets, preferably both, 15 are formed with diagonal ribs 27 which extend substantially from each corner of the sheet to the corner diagonally opposite. These ribs strengthen and rigidify the sheets as against the thrusts of the cargo. They 20 transmit any stress received at or near the middle of the sheet to the corners thereof and consequently to the framing of the car, that is, to the end sill, end plate and side girths to which the sheets are directly attached. The diagonal disposition of the 25 ribs 27 also gives the end structure very great capacity to withstand the weaving and other stresses to which the superstructure of the car as a whole is subjected due to causes 30 well known to railroad men. For example, they check any tendency that the sheets might have to bend or buckle when the stresses against the car are such as to cause the superstructure of the car to swing from 35 side to side or sag to one side or the other. Furthermore, these diagonally extending ribs withstand the tendency of the car to weave. A weaving strain carries one upper corner of the car farther forward than the 40 opposite upper corner and farther forward than the lower corner on the same side. This strain can only take place, provided the end structure be rigidly attached to the framing of the car, by bending or buckling 45 the end sheets on diagonal lines, and such bending is peculiarly well resisted by the disposition of the ribs 27.

The end sheets are divided by the diagonal ribs 27 into triangular spaces which are 50 reinforced by suitably formed ribs, the purpose of which is particularly to strengthen the sheets against local thrusts and pressures. Preferably the upper and lower triangular spaces 28 are formed with horizontal ribs 29 while the side spaces 30 are 55 formed with the vertical ribs 31. The vertical disposition of certain of the ribs increases the load bearing strength of the end structure. The ribs 29 and 31 also supplement the function of ribs 27 in strengthen-

ing and rigidifying the end structure as against weaving and other similar stresses.

I claim:

1. The combination with the framing of a box car comprising side girths, of a sheet 65 metal end structure comprising end sheets secured to said framing at the top and bottom and to the side girths, formed with diagonally extending ribs and with ribs in the spaces between said diagonal ribs. 70

2. The combination with the framing of a box car comprising side girths, of a sheet metal end structure comprising end sheets secured to said framing at the top and bottom and to the side girths, formed with 75 diagonally extending ribs and with sets of ribs some running horizontally and others vertically in the spaces between said diagonally extending ribs.

3. The combination with the framing of 80 a box car comprising an end sill, end plate, corner posts and side girths, of a metal end structure consisting of end sheets provided with flanges secured to said end sill, end plate and corner posts, gusset plates securing said end sheets to the side girths, the end sheet each being formed with rib extending from each corner to the corner diagonally opposite thereto so as to divide the sheet into triangular areas, the upper 85 and lower areas being formed with horizontal ribs and the areas at the sides with vertical ribs. 90

4. The combination with the framing of 95 a railway car comprising frame members extending longitudinally of the car, of a sheet metal end structure comprising an end sheet formed with diagonal ribs terminating adjacent to said longitudinal frame members.

5. The combination with the framing of 100 a railway car comprising frame members extending longitudinally of the car, of a sheet metal end structure comprising an end sheet formed with diagonal ribs terminating 105 adjacent to said longitudinal frame members, and with ribs in the spaces between said diagonal ribs.

6. A car end constructed of sheet metal in which is formed a centrally arranged, 110 horizontally disposed stiffening rib or corrugation, and the space above and below said horizontally disposed rib or corrugation being provided with diagonally disposed intersecting stiffening ribs or corrugations.

WALTER P. MURPHY.

It is hereby certified that in Letters Patent No. 1,263,458, granted April 23, 1918, upon the application of Walter P. Murphy, of Chicago, Illinois, for an improvement in "Sheet-Metal End Structures for Railway-Cars," errors appear in the printed specification requiring correction as follows: Page 2, line 87, claim 3, for the word "sheet" read *sheets*, and same page, line, and claim for the word "rib" read *ribs*; and that the said Letters Patent should be read with these corrections therein that the same may conform to the record of the case in the Patent Office.

Signed and sealed this 21st day of May, A. D., 1918.
